UNITED STATES PATENT OFFICE

DOUGLASS C. FONDA, OF WEST ORANGE, NEW JERSEY, ASSIGNOR TO NIXON VENDING AND CHANGE MAKING MACHINES, INC., OF NEW YORK, N. Y., A CORPORATION OF DELAWARE

VENDING CABINET

Application filed March 11, 1927. Serial No. 174,549.

This invention relates to vending cabinets for toilet articles, its chief object being to provide a construction of this kind for use in washrooms and bathrooms of hotels, clubs and other public establishments where it may be desirable or advantageous to vend toilet goods and accessories of all kinds to patrons.

A main object of the present invention is to provide a cabinet involving a construction of means whereby the door element will be secured in closed position against access to the goods contained within the cabinet, and whereby upon the deposit of a proper purchase coin the door element may be readily opened by the purchaser, who is thereupon put in possession of the goods purchased.

Another object of the invention is to provide a cabinet involving a construction of means which will permit the owner or his authorized attendant to open the door element without the deposit of a purchase coin.

A further object of the invention is to provide for a cabinet or similar article holding structure a novel coin-operated door control which will be simple and economical to manufacture and highly efficient in use.

Other objects will appear hereinafter.

The invention consists in the combination and arrangement of parts hereinafter described and claimed.

The invention will be best understood by reference to the accompanying drawing forming a part of this specification, and in which:

Fig. 1 is a perspective view of a cabinet made in accordance with the present invention;

Fig. 2 is a fragmental vertical sectional view, taken on a larger scale than the view of Fig. 1 and approximately on the line 2—2 thereof;

Fig. 3 represents a cross section taken on the line 3—3 of Fig. 2; and

Fig. 4 represents a fragmental vertical section taken on the line 4—4 of Fig. 2.

Referring to the drawing, where a selected embodiment of the invention has been illustrated, 5 denotes a cabinet or casing interiorly divided into an upper or stock compartment 6 and a lower or money compartment 7

by a floor 8 located an appreciable distance above the base plate 9. For closing the upper or stock compartment a front door 10 is employed, this door being preferably secured for opening and closing movement by a suitable hinge 11 extending along one vertical edge. With this hinge is associated a spring 12, arranged to close the door automatically and to keep it closed at all times. Near its free edge the door 10 is provided with an exterior knob 13 by which it is manually opened, and below said knob there is a coin deposit slot 14 for receiving the purchase coins. For the lower or money compartment 7, which serves as a cash box, there is a front door 15 preferably hinged as at 16 at its lower horizontal edge so as to open outwardly and downwardly. For manually opening and closing the door 15 a finger piece 17 is provided; and in order that no one except the owner or authorized attendant may have access to the cash compartment, this door is equipped with a suitable key operated lock 18.

In its preferred form of construction as illustrated in the accompanying drawing, the coin operated control for the upper door 10 comprises a coin holding structure including oppositely disposed end walls or jaws 19 and 20 arranged at the bottom of the stock compartment at the floor 8 and spaced apart to receive snugly between them the purchase coin as 21 as it drops from the downturned end 22 of the coin chute 23 down which the coin has rolled on its circumference after having been inserted through the coin deposit slot 14. The jaws 19 and 20 as well as the chute 23 are supported upon the side 24 of the cabinet, said side being preferably thickened or built out at 25 for this purpose. The jaw 19 and chute 23 are made fast to the casing side, while the jaw 20 is mounted for pivoting upon a stud 26. In the construction shown, the portion 25 of the casing side constitutes a backing wall or sheet for the chute 23 and for the coin pocket 27 between said jaws 19 and 20 and defined at the inner side by flanges 28 and 29 formed, respectively, on said jaws. To sustain the coin within the pocket and between the jaws, the pivotally

mounted jaw 20 near its lower end is furnished with a pin 30 which extends transversely of the coin engaging edge of said jaw at a suitable point inwardly of the free edge of the flange 29.

According to an important feature of the invention, the pivotally mounted jaw 20 is made at its top end with a forwardly projecting arm 31 having a hook 32 adapted to interlock with the notch 33 of the lug or catch piece 34 rigid with the door 10. Said hook 32 enters and leaves the notch 33 by a slideway 34' at top of which is a seat preferably comprising the end of an adjusting screw 35 which is screw-threaded upwardly through the catch piece. The jaw 20 is set or positioned so that a deposited coin of proper denomination will drop into the pocket between the two jaws and be sustained therebetween by the pin 30 when the hook rests upon the adjusting screw; and it will be observed in this connection that by manipulating the adjusting screw the entrance gap between the jaws may be finely adjusted. The hook is normally urged into engagement with its seat and upon leaving its seat, into engagement with its notch, by a spring 36 held in tension by stud 26 and having one end attached at 37 to the arm 31 and the other end extending over post 38 on jaw 19. By this arrangement, upon attempting to open the door 10 when there is no coin between the jaws 19 and 20, the hook on leaving its seat will slip into the notch. A slight outward movement of the door will thus result in locking the door and preventing access to the stock compartment. When, on the other hand, a coin has been deposited and reposes between the jaws, such deposited coin will maintain the pivotally mounted jaw against turning when the seat for the hook is withdrawn under the opening movement of the door, with the result that the hook will escape engagement with the notch, permitting the door to be fully opened; and it will be noted in this connection that the lug or catch piece 34 is made with an inclined abutment 39 with which the hook is engaged during the withdrawal of the catch piece, so that the pivotally mounted jaw will be turned in a direction to effect a discharge of the sustained coin during the opening movement of the door. The discharged coin drops through an opening 4 in the floor into the cash compartment below.

In order that the owner of the cabinet or his authorized attendant may have access to the stock compartment without inserting a purchase coin, the jaw 20 is furnished with a finger piece 41 which projects downwardly through the opening 40 into the cash compartment 7 where, upon unlocking and opening the door 15, it may be seized so as to manually maintain the jaw 20 until the door 10 has been opened.

As previously pointed out, the door 10 is

automatically closed under the influence of the spring 12; and it will be understood from an inspection of the drawing that each time the door is closed, the hook is raised by the slideway and reseated upon the adjusting screw, so that the pivotally mounted jaw will be set and positioned for the reception of the purchase coin.

When the door 10 has been opened far enough to give free access to the stock compartment, the hook will drop down over the inner end 42 of the catch piece, which inner end will thereupon act as a stop preventing the closing of the door until the hook, through the manual pivoting of the jaw 20, has been raised again to clear said inner end. When, therefore, the door 10 is not completely closed, it is an indication that the stock has been sold.

Preferably and as shown, a shield 43 is arranged about the chute, jaws and associated parts so as to protect the same. The stock compartment may be subdivided in any manner desired; and the door 10 is preferably provided with a glass pane 44 through which the stock may be observed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim is:

1. A vending cabinet having a door attached thereto for opening and closing movement and provided with a catch piece; and a coin holding pocket structure within the cabinet including a swingable end wall having thereon a projecting hooked arm adapted to rest upon said catch piece to maintain said end wall in place for admitting a coin into said pocket structure when said door is closed and adapted also to be itself maintained in position from where it will automatically interlock with said catch piece consequent upon the opening movement of said door, substantially as described.

2. A vending cabinet having a door attached thereto for opening and closing movement and provided with a catch piece; a coin holding pocket structure within the cabinet including a swingable end wall having thereon a projecting hooked arm adapted to rest upon said catch piece to maintain said end wall in place for the reception of a coin in said pocket structure when said door is closed and adapted also to be itself maintained in position from where it will automatically slide into interlocking engagement with said catch piece consequent upon the opening movement of said door; and said end wall with its hooked arm being adapted to be sustained independ-

ently of said catch piece by a coin in said pocket structure to prevent such interlocking action, substantially as described.

3. In a vending cabinet, a door mounted for opening and closing movement; a projection on said door provided with a notch and a slide-way; a coin holding pocket structure including a swingable end wall; a projecting hooked arm on said end wall adapted to have support on said projection to maintain said end wall in place for the reception of a coin in said pocket structure when said door is closed and adapted also to be itself maintained in position from where it will pass downward and upward on said slideway into and out of interlocking engagement with said notch consequent upon the opening and closing movement of said door, substantially as described.

4. In a vending cabinet, the combination with an openable door provided with a catch, of coin holding mechanism including a pivotally mounted jaw; a projecting arm on said jaw by which to turn the same on its pivot and hooked to have interlocking action with said catch consequent upon the opening movement of said door; and an adjustable element carried by said catch and constituting a rest for said hooked arm to adjust the position of said jaw and hooked arm, substantially as described.

5. In a vending cabinet, the combination with an openable door and a side plate, of a coin deposit chute constructed with said side plate and having a downturned delivery end; a pair of spaced jaws associated with said side plate to constitute a coin receiving pocket therewith at the delivery end of the chute, one of said jaws being fixed and the other being pivoted; an arm extending from the pivoted jaw; a projection on said openable door constituting a support for said arm including an adjustable element for critically adjusting the pivoted jaw relatively to the fixed jaw; and spring means for placing the pivoted jaw under tension to urge said arm into engagement with the adjustable element, substantially as described.

6. In combination, an openable door a side sheet; a pair of spaced jaws associated therewith to constitute a coin receiving pocket; one of said jaws being fixed to said sheet and the other being pivoted thereto; flanges on the confronting ends of said jaws in opposed relation to said sheet; a transverse pin fixed on the pivoted jaw inwardly of the free edge of its flange for engaging the circumference of a coin entered into said pocket and thereby to retain the same between said jaws; a projection on said openable door for maintaining said pivoted jaw in set position; and means for swinging said pivoted jaw from set position, substantially as described.

7. A vending cabinet comprising a door with a catch; a coin receiving pocket structure including a pivotally mounted end wall

having an outwardly projecting hooked arm adapted to interlock with said catch; said end wall being pivoted near its top end with its depending lower portion swingable inwardly of the pocket structure; said hooked arm being normally supported at its free end on said catch so that, upon the opening movement of the door, it will swing into interlocking engagement with said catch as said lower portion swings inwardly of the pocket structure; said lower portion being adapted to abut on a coin introduced into the pocket structure and thereby to serve as a stop for preventing swinging movement of the end wall in a direction to effect engagement of the hooked arm with said catch, substantially as described.

8. A vending cabinet comprising a door with a catch; a coin receiving pocket structure including a pivotally mounted end wall having an outwardly projecting hooked arm adapted to interlock with said catch; said end wall being pivoted near its top end with its depending lower portion swingable inwardly of the pocket structure; said hooked arm being normally supported at its free end on said catch so that, upon the opening movement of the door, it will swing into interlocking engagement with said catch as said lower portion swings inwardly of the pocket structure; said lower portion being adapted to abut on a coin introduced into the pocket structure and thereby to serve as a stop for preventing swinging movement of the end wall in a direction to effect engagement of the hooked arm with said catch; and a finger piece on said end wall by which manually to swing the same on its pivot, substantially as described.

9. A vending cabinet comprising a door with a catch; a coin receiving pocket structure including a pivotally mounted end wall having an outwardly projecting hooked arm adapted to interlock with said catch; said end wall being pivoted near its top end with its depending lower portion swingable inwardly of the pocket structure; said hooked arm being normally supported at its free end on said catch so that, upon the opening movement of the door, it will swing into interlocking engagement with said catch as said lower portion swings inwardly of the pocket structure; means on said lower portion for sustaining a coin introduced into the pocket structure; said lower portion being adapted to abut on a coin sustained in the pocket structure and thereby to serve as a stop for preventing swinging movement of the end wall in a direction to effect engagement of the hooked arm with said catch, substantially as described.

In testimony whereof, I have signed my name to this specification.
